UNITED STATES PATENT OFFICE.

GEORGE B. THOMAS, OF BRIDGEPORT, CONNECTICUT, ASSIGNOR TO THE PERKINS ELECTRIC SWITCH MFG. COMPANY, OF BRIDGEPORT, CONNECTICUT, A CORPORATION OF CONNECTICUT.

ROTARY SNAP-SWITCH.

982,549.

Specification of Letters Patent. Patented Jan. 24, 1911.

Application filed August 14, 1908. Serial No. 448,547.

To all whom it may concern:

Be it known that I, GEORGE B. THOMAS, a citizen of the United States of America, residing in the city of Bridgeport, in the 5 county of Fairfield, in the State of Connecticut, have invented certain new and useful Improvements in Rotary Snap-Switches, of which the following is a specification.

My invention relates to that class of electric switches of the rotary snap type, in which there is an operating spindle and a spring to be tensioned thereby, a flat fixed ratchet or equivalent stop plate on the insulating base, a radially movable latch to 15 engage the stops and operated by the turning of the spindle to disengage the latch from the stops.

The object of my invention is to simplify and improve the construction and operation 20 of the switch and particularly of the latching means.

In the accompanying drawing Figure 1 is a vertical section of a rotary snap switch embodying my invention; Fig. 2 is a sectional plan on the line 2—2, Fig. 1; Fig. 3 is a similar view, but showing the parts in changed positions; Figs. 4 and 5 are corresponding sectional plan views, taken on the line 4—4, Fig. 1; Fig. 6 is a perspective 30 view of a detail.

In Fig. 1 I have shown the spindle A as mounted to turn in a suitable bearing b secured in the insulating base B, and on the spindle is any suitable operating handle a 35 and any suitable switch plate S having insulated clips or blades adapted to make and break contact with the blades or clips of binding posts D on the base. There is the usual play rotarily between the spindle and the plate with an intermediate spring E coiled about the spindle connected at its upper end to a crown piece e on the spindle, and at its lower end bearing upon a finger 7 upon the switch plate S, (Figs. 2 and 3). 45 A cover C with insulating lining is provided as usual.

Upon the inner face of the base B is a stop plate F in the form of a four-toothed ratchet plate secured to the base in any convenient way. With the ratchet of this top

plate engages the downwardly projecting finger 8 on the end of a curved latch bar G, which is pivoted at its other end at 9 to a crank arm H secured to the spindle A, so as to turn with it, as by fitting a squared hole 55 in the arm H over a correspondingly squared portion of the spindle.

The switch plate S is provided with a radial guide arm 10 (Figs. 2 and 3) against which bears an upwardly projecting finger 60 11 on the end of the latch bar G.

When the spindle A is turned clockwise, as usual, the spring E will tend to carry the switch plate S (Fig. 2) with it, but the latch bar with its lower finger bearing 65 against the radial edge of a tooth of the stop plate F and with its upper finger bearing against the radial arm 10 of the switch plate will retain the latter, and the spring E will be tensioned. But the turning of the 70 spindle A meantime will turn its crank arm H from the position Fig. 4 to the position Fig. 5, and thereby cause the latch bar to slide along the radial face of the stop tooth and finally escape beyond it, whereupon the 75 tensioned spring E will cause the switch plate to fly forward, but in doing so its arm 10 will throw the latch bar forward also and thereby draw its outer end radially inward and cause its finger 8 to engage the next 80 succeeding tooth of the stop plate F.

I claim as my invention—

1. A rotary snap switch, having a base and stops thereon with an operating spindle carrying a crank arm, a latch bar pivoted to 85 said crank arm, and adapted to engage the stops, a switch plate with which the latch bar is in sliding engagement and a tensioning spring between the spindle and switch plate. 90

2. A rotary snap switch, having a base and ratchet stops thereon with an operating spindle carrying a crank arm, a latch bar pivoted to said crank arm, a switch plate and a tensioning spring between the spindle 95 and switch plate, the latch bar having an upwardly projecting finger in sliding contact with the switch plate and a downwardly projecting finger to engage the ratchet stops.

3. A rotary snap switch having a base and 100

stops thereon with operating spindle carrying a crank arm, a latch bar pivoted to said crank arm and provided with one lug to engage the stops, and a second lug in sliding engagement with the switch plate, together with a tensioning spring between the spindle and switch plate.

In testimony whereof I have signed my name to this specification, in the presence of two subscribing witnesses.

GEORGE B. THOMAS.
